UNITED STATES PATENT OFFICE.

THOMAS R. BROWN, OF SPARKILL, NEW YORK, ASSIGNOR TO THE WESTINGHOUSE AIR BRAKE COMPANY, OF WILMERDING, PENNSYLVANIA, A CORPORATION OF PENNSYLVANIA.

AUTOMATIC CAR, TRAIN PIPE, AND ELECTRIC COUPLER.

Application filed March 6, 1917. Serial No. 152,695.

To all whom it may concern:

Be it known that I, THOMAS R. BROWN, a citizen of the United States, residing at Sparkill, in the county of Rockland and State of New York, have invented a certain new and useful Improvement in Automatic Car, Train-Pipe, and Electric Couplers, of which improvement the following is a specification.

10 This invention relates to couplers for cars, and in which means are also provided for making the train pipe connections, and for coupling the electric train wires between the cars of the train. I have heretofore designed various forms of couplers for this purpose, and in which each coupler is formed of a body or casing having a movable lock for engaging a counterpart coupler head, and also provided with one or more 20 passages having gasket openings for connecting with corresponding openings in a counterpart coupler for fluid pressure conduits. These couplers have also been provided with electric portions, usually in the form of a casing secured to the bottom of the coupler body, and containing a plurality of electric contacts connected to the respective car line circuits, and a movable contact carrier or slide having corresponding contacts and adapted to be projected into the corresponding casing of a counterpart coupler for establishing electrical connection between the corresponding circuits of the respective cars.

25 Fluid pressure means have been employed for releasing the coupler locks, for operating the valves in the fluid pressure train pipe conduits, and for projecting the contact carrier or slide of the electric portion, these devices being controlled by a manually operated valve usually located in the cab at the end of the car.

There are certain relations which should be preserved between the operations of these devices, for instance, the contact carrier or slide of one of the couplers should not be projected until the coupler heads are securely locked together, as otherwise breakage or damage to said slide is liable to result, and one of the objects of my present improvement is to provide for ensuring the locking of the couplers before the slide can be projected.

In the electric portions as heretofore de-

signed, the slide has been so located as to be projected against the slide in the counterpart coupler and force the same inward against a spring to the coupled position, and in releasing, the spring operates to return both slides to their normal positions, each within its respective casing. According to my present improvement, however, each slide or contact carrier is located back of the car circuit contacts, and is not moved by the slide of the other coupler when projected into its casing for making the electric connections. Each slide is actuated independently of the other by its respective piston in both the projecting and withdrawing movements, and no springs are required in the operation. During the coupling action, the slides are held in their retracted position by fluid pressure controlled by the position and movement of the coupler locks.

Another feature of my present improvement relates more particularly to the type of coupler in which the counterpart heads approach each other, in a lateral or diagonal direction, and comprises the location of the electric portion and slides so that they are projected in a line with the diagonal direction of approach of the couplers, whereby in case of an accidental pulling apart of the couplers before the slide is withdrawn, the same will not be damaged or broken, as it will be drawn out of the opposite casing in line with its usual movement and without injury.

Still another feature of my invention comprises improved covers, or shutters for covering and protecting the contact carrier or slide, and for closing the opening in the casing when the slide is in the retracted position and the couplers are separated.

Another object is to provide an improved form of closing valve for the train pipe passages, and means for effecting their closing operation at the same time as releasing the coupler locks and withdrawing the slide.

These and other objects will now more fully appear from the following description of a preferred form of constructions, and the novel features will be set forth in the claims.

In the accompanying drawings: Figure 1 is a diagrammatic sectional view showing the various portions of two couplers em-

bodying my improvements, coupled together; Fig. 2, a plan of same; Fig. 3, a plan showing, in detail, the adjoining ends of the slides of the two couplers; Fig. 4, a 5 vertical section of the electric portion showing the shutters closed; and Fig. 5, a transverse section of the electric portion taken on the line 5—5 of Fig. 1.

According to the construction shown, my 10 improvement is applied in connection with a coupler of the rigid lock type, that is, one in which the counterpart couplers are each provided with projecting portions having vertical plane surfaces arranged in an inclined or diagonal direction, whereby the 15 couplers engage each other with a relative longitudinal and lateral movement during the coupling action, and each coupler also having a pivoted lock or cam lever adapted 20 to be automatically clamped against a corresponding surface on the counterpart coupler.

These locking levers, 6, are normally pressed outward by the springs, 7, acting on 25 the pistons, 8, mounted in cylinders, 9, and connected by rods, 10, with the pivoted locks for releasing the same with fluid pressure admitted to said cylinders. The body portion, 11, of the coupler contains the passages 30 for the fluid pressure conduits, such as the reservoir line connection, 12, and the train brake pipe passage, 13, said passages being formed in a diagonal direction in line with the approach movement of the coupler heads 35 and provided with suitable gaskets at the meeting face of the coupler located at right angles to said passages. In the main reservoir passage are placed the valves, 14, having stems, 15, extending out through the 40 gasket openings and adapted to engage each other and thereby open the valves in the two couplers when the same are brought together. The train brake pipe passages are controlled by the piston valves, 16, having 45 springs, 17, for normally closing said valves against their seats, the pressure in the chamber back of each piston valve being governed by a small valve, 18, having a stem, 18^a, actuated by a piston, 19, in chamber, 20, for 50 controlling the port, 21, communicating with a pipe, 22, which may be connected with a manually operated valve. A supply port, 23, leads from the main reservoir passage to the piston chamber, 20.

55 The electric portion of the coupler comprises a casing, 24, adapted to be bolted or otherwise secured to the bottom of the coupler body and positioned in a laterally inclined or diagonal direction parallel with 60 the direction of approach of the coupler heads, as shown particularly in Fig. 2, said casings containing a plurality of electric contacts, 25, connected to the respective car circuit wires, 26, and provided with a contact carrier or slide, 27, having correspond-

ing contacts, 28, and operated by a piston, 29, located in cylinder, 30. The casing of the electric portion has an opening at its forward or outer end adapted to register with the corresponding opening of the electric portion of a counterpart coupler when the same are brought together for coupling, and through which openings the contact slide of either one of said couplers is adapted to be projected for the purpose of establishing electrical connection between the corresponding car line circuits upon the adjacent cars. 70

According to one of the features of my present improvement, the normal release position of the contact slide, 27, is in the rear of the fixed electric contacts, 25, as shown at the right in Fig. 1, so that the slide which is projected through the openings to bridge over the space and make electrical connection between the couplers does not move the slide of the other coupler which remains in its retracted position, but simply moves far enough for its electrical contact bars to engage the sets of stationary contacts in the two casings, as shown in Fig. 90

1. In this form of construction the slide is projected by admitting fluid to one side of its actuating piston, and is retracted by admitting fluid to the reverse side of said piston, there being no springs to oppose the movement in either direction, and the piston and slide simply remaining in either position by inertia and the friction of the parts. 95

Another feature of my improvement comprises improved covers or shutters, 31, for protecting the electric portion and slide against the weather when the slide is in its normal retracted position within the casing. These shutters or covers which enclose the electric contacts and slide are formed in upper and lower halves, similar to a clam shell, and swing on pivots, 32, so as to meet at their front edges and completely close the opening in the casing. The covers are provided with projections or bosses, 33, upon their inner surfaces, for engagement with inclined surfaces upon the slide when in its retracted position for the purpose of causing an opening of the shutters or covers on one coupler by the preliminary movement of the slide of the same coupler. In order to open the shutters of the other coupler each slide is provided with a wedge shaped projection, 34, at one side, and a corresponding notch at the other side, as shown particularly in Fig. 3. These wedge shaped projections and notches are made right and left so that the projection of one slide may pass within the notch on the opposing slide at the extreme projected positions, as will be readily understood. 110

In order to close certain circuits upon a car when it is at the end of a train or operated as a single car, one of the swinging 115

covers or shutters, 31, may be provided with a contact bar, 35, adapted to close such local circuit by connecting contact fingers, 36, when the covers are closed, but also adapted 5 to open said circuit when the covers are moved to the open position, as when one of the slides is projected. It will be seen that when the couplers are separated and the slide withdrawn, the covers completely surround 10 the electric contacts and slide, and close the opening in the casing, thereby fully protecting the electric portion from injury and from exposure to dirt, dust, and the weather.

15 A manually operated valve may be employed for controlling the supply of air through pipes, 37 and 38, to opposite ends of the cylinder, 30, for shifting the slide to its projected or retracted positions, and 20 when air is admitted through pipe, 38, to the outer end of the cylinder for withdrawing the slide, it also flows through passages, 39, and hollow tappets, 39^a, to the corresponding end of the cylinder, 30, on the adjacent coupler, whereby both slides will be held in their retracted positions.

According to another feature of my improvement, the movement of the coupler lock controls a supply of fluid to the cylinders, 30, for holding the slides in the retracted position until the coupler locks have sprung into their locked positions. One form of valve means for this purpose is shown as comprising a casing, 40, containing valve, 41, having a stem, 42, actuated by a projection, 43, on the rod, 10, of the lock releasing piston, 8. A spring, 44, tends to hold the valve seated, and the casing is connected to a supply pipe, 45, and an outlet pipe, 46. The manually operated valve, 50, for controlling the various parts of the coupler may be located in the cab at the end of each car, and has a casing, 51, attached to the pipes, 37, and 22, and also a supply pipe, 52. In the normal intermediate or neutral position of the valve, 50, as shown, the pipes, 37 and 22, are both open to exhaust to the atmosphere, the valve being turned in one direction to supply fluid from 50 pipe, 52, to the pipe, 22, and in the opposite direction to supply fluid to the pipe, 37. A double check valve device, 53, containing valve, 54, and spring, 55, is connected between the pipes, 22, 38, and 46, for permitting the passage of fluid from either pipe, 22 or 46, to the pipe, 38, but preventing back flow to either pipe, 22 or 46, when fluid is being supplied through the other.

60 The operation of my improved device is as follows: When the couplers are brought together in the act of coupling, the stems, 15, of the valves, 14, in the main reservoir line passage engage each other and cause an unseating of the valves, 14, and permits 65 air from the main reservoir pipe to flow

through the coupling and equalize on the two cars. At the same time air flows through the port, 23, into the chamber, 20, forcing the piston, 19, against the stem, 18^a, to unseat the small vent valve, 18, thereby 70 releasing air under pressure from the back of the piston valve, 16, in the brake pipe passage, 13, and causing said brake pipe valve to open by the pressure from the brake pipe passage acting upon its opposite face. This valve is thus forced back against its spring, 17, until it seats against a gasket ring, as indicated, thereby preventing leakage around the valve, and holding the same in the full open position. 80 The space back of pistons, 16 and 19, is then in communication with the atmosphere through the port, 21, pipe, 22, and exhaust ports of the valve, 50.

During the coupling action, as the couplers approach each other, the projecting portion of one coupler head engages the pivoted lock, 6, of the other coupler, and depresses the same in the well known manner. This movement operates through the 90 rod, 10, and piston, 8, to partially compress the spring, 7, and by moving the projection, 43, against the stem, 42, of the valve, 41, opens the same to permit air from the supply pipe, 45, to flow to pipe, 46, to check 95 valve, 53, where it acts on the valve, 54, to close the outlet to pipe, 22, and then flows through pipe, 38, to cylinder, 30, thereby forcing and holding piston, 29, and slide, 27, in the retracted position. Air 100 also flows through passages, 39, and hollow tappets, 39^a, to the cylinder, 30, of the opposite coupler for the same purpose. The action of the check valve, 54, prevents air pressure from passing to the pipe, 22, and the cylinders, 9 and 20, at this time, and these cylinders are in connection with the exhaust through valve, 50, so that no pressure can accumulate in the releasing cylinders, 9, but the pressure at the outer ends 105 of cylinders, 30, on pistons, 29, insures that these pistons and their slides will be in the retracted position during the coupling action.

As soon as the couplers reach the full 115 coupled position, the spring, 7, forces the lever, 6, into its locked position against the counterpart coupler, and moves the rod, 10, and projection, 43, away from the stem, 42, to allow the valve, 41, to close by means of its spring, 44. This cuts off the supply of air to the pipes, 46 and 38, and cylinder, 30, and permits the exhaust of such air to the atmosphere through the grooves in the stem, 42. A similar operation occurs on the 120 opposite coupler, and completes the coupling up of the car, and the air connections, and the automatic opening of the valves in the latter passages. It will also be apparent that neither slide can be projected 125 130

until both of the coupler locks have moved to their proper positions and the couplers are securely locked together.

The electric portions of the couplers are

- 5 then facing each other with their openings in register, and the covers closed with the slides in the retracted position, as above described. The connection of the electric circuits through the coupler is then made by manually turning one of the valves, 50, to the coupling position for admitting air from the supply, 52, to the pipe, 37, leading to the inner end of one cylinder, 30, causing the piston, 29, therein, to move outward and 10 project its slide through the opening into the casing of the other coupler to such position that the contacts, 28, establish electrical connection between the contacts, 25, of the two couplers and the corresponding train 15 line circuits, 16, the contacts, 28, being properly cross-connected as before explained. Only one of the slides, 27, is thus projected, as the other slide is not moved but remains in its retracted position, as shown. During 20 the outward movement of the slide, it operates to open the respective sets of covers or shutters, 31, as above described, and as the covers are swung open upon their pivots, the local circuits at the contacts, 35 and 36, 25 are broken. The slide then remains in its projected position with the electric circuits connected during the running period, although the manual valve, 50, is turned back to its neutral position, and the air from cylinder, 30, and pipe, 37, is exhausted to the atmosphere.

- When it is desired to uncouple the cars, the valve, 50, upon one of the cars is turned to the uncoupling position, in which air is supplied from pipe, 52, to the pipe, 22, communicating with cylinders, 9 and 20, and through check valve device, 53, and pipe, 38, with the outer end of cylinder, 30. Air also flows through passages, 39, and 40 connecting tappets, 39^a, to the corresponding parts of the other coupler. The slide, 27, which was projected, is thereby withdrawn by its piston, 29, and the shutters, 31, are automatically closed as the slide is moved to its retracted position. If desired, springs, 56, may be employed to assist in the closing movement of the shutters. The contact, 35, also closes the local circuit at points, 36, when the shutters reach the closed position. 45 At the same time, the air passing into the unlocking cylinder, 9, forces the piston, 8, outward and releases the coupler lock, 6. As the air also flows through the port or passage, 21, and into the chamber back of the 50 closing valve piston, 16, the pressure equalizes thereon and the spring forces the valve to its seat and closes the train brake pipe passage. As similar operations are performed on both couplers, due to the air connection through the hollow tappets, the un-

coupling action is complete, and the couplers may then be pulled apart. When this occurs, the main reservoir line valves automatically close and air escapes from chamber 20 through passage 23. Air also escapes 70 through the open tappets, 39^a, from pipes 38 and 22, cylinder 9 and passage 21, and this permits a return to the normal closed position of the small vent valve, 18, by the air under pressure from the train pipe which 75 leaks around the piston 16.

When the unlocking pistons are moved outward in releasing the coupler locks, the valve, 41, will also be opened, which will incidentally permit an additional supply of 80 air under pressure to assist in the releasing action and help offset any leakage between the tappets, 39^a, although this supply is not essential to the operation of the device.

In the event of an accidental parting of 85 the couplers, the valve, 16, in the brake pipe, will not close immediately, as there is only atmospheric pressure back of the valve, and it will remain in its open position until the brake pipe pressure acting on the face 90 of the valve has diminished below the force of the spring, 17. This reduction in brake pipe pressure, during this period of time, will be sufficient to cause a full application 95 of the automatic brakes.

Having now described my invention, what I claim as new and desire to secure by Letters Patent is:

1. In a coupler, the combination with a casing, and a movable lock operated automatically upon the coming together of the counterpart couplers to lock the same together, of electric contacts connected to the respective car line circuits, a movable contact carrier, a fluid pressure device for operating said carrier, and means governed by the movement of the coupler lock for supplying fluid to said device to prevent the outward movement of the carrier. 100

2. In a coupler, the combination with a 110 casing, and a movable lock operated automatically upon the coming together of the counterpart couplers to lock the same together, of electric contacts connected to the respective car line circuits, a movable contact carrier, a piston for actuating said carrier, and a valve controlled by the movement of the coupler lock for supplying fluid to said piston to prevent outward movement of the carrier. 115

3. In a coupler, the combination with a casing, a movable lock, and a device for releasing said lock, of electric contacts connected to the respective train line circuits, a movable contact carrier adapted to be projected into a counterpart coupler for establishing electrical connections with the corresponding contacts therein, a piston for projecting said carrier, and means governed by the movement of said lock for controlling 120

- a supply of fluid pressure to hold the carrier in its retracted position.
4. In a coupler, the combination with a casing, a movable lock, and a device for releasing said lock, of electric contacts connected to the respective train line circuits, a movable contact carrier adapted to be projected into a counterpart coupler for establishing electrical connections with the corresponding contacts therein, a piston for retracting said carrier, and a valve governed by the movement of the lock for controlling a supply of fluid to said piston for holding the carrier in its retracted position.
- 15 5. In a coupler, the combination with a casing, and a movable lock operated automatically upon the coming together of the counterpart couplers to lock the same together, of electric contacts connected to the respective car line circuits, a movable contact carrier, a piston for retracting said carrier, a manually operated valve for controlling a supply of fluid to said piston, and a valve governed by the movement of the 25 coupler lock for also supplying fluid to said piston.
6. In a coupler, the combination with a casing, and a movable lock operated automatically upon the coming together of the counterpart couplers to lock the same together, of electric contacts connected to the respective car line circuits, a movable contact carrier, a piston for retracting said carrier, a manually operated valve for controlling a supply of fluid to said piston, a valve governed by the movement of the coupler lock for also supplying fluid to said piston, and a check valve located between said controlling valves and said piston.
- 40 7. In a coupler, the combination with a casing, and a movable lock operated automatically upon the coming together of the

couplers to lock the same together; of electric contacts connected to the respective train line circuits, a movable contact carrier, a piston for actuating said contact carrier, and a valve governed by the movement of the lock for controlling a supply of fluid to, and an exhaust from, one side of said piston.

8. The combination with a vertical plane coupler in which the counterpart coupler heads approach each other in a lateral or diagonal direction in the act of coupling, of an electric portion having contacts connected to the respective car line circuits, a contact carrier, and means for projecting said carrier in a direction parallel with the diagonal approach movement of the coupler heads to electrically connect the corresponding contacts of the counterpart couplers.

9. The combination with a vertical plane coupler in which the counterpart coupler heads approach each other in a lateral or diagonal direction in the act of coupling, of an electric portion having contacts connected to the respective car line circuits, a contact carrier, and a piston for actuating said carrier, said piston and carrier being so located as to move in a direction parallel with the diagonal approach movement of the coupler heads.

10. In a coupler, the combination of a casing containing electric contacts connected to the respective car line circuits, a movable contact carrier, and a pair of pivoted covers for enclosing said contacts and the carrier and closing the opening in the casing, said contact carrier having a wedge shaped projection for opening the pivoted covers of a counterpart coupler.

In testimony whereof I have hereunto set my hand.

THOMAS R. BROWN.
